UNITED STATES PATENT OFFICE.

HEINRICH SCHWARZ, OF VIENNA, AUSTRIA-HUNGARY.

ROOF.

1,024,808.

Specification of Letters Patent.

Patented Apr. 30, 1912.

Application filed August 4, 1911. Serial No. 642,315.

To all whom it may concern:

Be it known that I, HEINRICH SCHWARZ, subject of the King of Hungary, residing at Vienna, in the Empire of Austria-Hungary, have invented certain new and useful Improvements in Roofs, of which the following is a specification, reference being had therein to the accompanying drawing.

It is known to form ornamental roofs by arranging flap-like serrated strips in such a manner, that each strip lying above the adjacent one covers the row of nails serving to secure the lower one and any joints of the same.

15 The subject of the present invention consists of a further development of this kind of roof covering, and is characterized by the fact that the strips arranged one over the other, more particularly at those places 20 which are not covered by the adjacent higher layer are provided with a metallic or equivalent covering.

25 The arrangement may be either so carried out that the roof covering is made up of continuous courses of serrated material or that the same consists of single flap like parts laid side by side with edges abutting, and the sheet metal material for covering the flaps may also either consist 30 of single pieces or form continuous bands to cover a number of flaps.

In the accompanying sheet of drawings the modifications arising from the said possibilities are shown as follows:

35 Figure 1 represents a continuous flap-like serration composed of course or strips z of roofing material such as cardboard, felt, canvas, jute or the like, from the symmetrical arrangement of which arise the parts m

40 corresponding with the single flaps, as shown in Fig. 2. Fig. 3 represents an angular sheet metal piece n cut for the roofing material. The full lines indicating the cuts

45 necessary to give the desired forms and the dotted lines indicating the edges along which the sheet metal is bent to form it into the metal covering. Figs 4, 5 and 6 represent the finished metal covering n in plan, horizontal section on A B and vertical section

50 on C D. Figs 7, 8 and 9 represent a cardboard roofing piece m provided with the partial covering n , in plan, horizontal section on E F and vertical section on G H.

55 Fig. 10 represents a roof formed of the elements m, n shown in Figs. 7, 8 and 9. Fig. 11 represents a roof formed of the con-

tinuous courses z shown in Fig. 1 and the sheet metal coverings n shown in Figs. 4, 5 and 6.

The courses shown in Fig. 1 are cut in 60 the known manner from a complete course in such a way that two coincident half courses are formed, which have flap like projections on their longitudinal edges of such a form that the spaces between the same 65 coincide with the said projections. By dividing up the strips z shown in Fig. 1 the pieces m shown in Fig. 2 are provided, these pieces m having quadrangular upper portions and tapering lower portions. 70

The roof is formed either with the continuous course z or the single pieces m ; the formation of the sheet metal covering is the same in both cases.

75 The sheet metal pieces which serve to cover the projecting parts of the flaps shown in Figs. 1 and 2, are cut out of sheet metal in square pieces (Fig. 3). These pieces are provided with two cuts h, h lying in one diagonal and two short cuts t, t running 80 parallel with the second diagonal, and then the parts between the said cuts are bent as shown in dotted lines in Fig. 3, in such a manner that, as may be seen from Figs. 4, 85 5 and 6, the side edges a are at a distance 85 equal to the single thickness of the roofing material from the body of the piece whereas the tongue o at the point is at a distance 90 equal to the double thickness of the said roofing material. The covering piece so 95 formed is then slid on the roofing piece shown in Fig. 2, as shown in Fig. 7, so that the fold a of the same reaches over the edge of the projecting flap and the body of the sheet metal when the material is placed in 100 position, covers the parts left free. The material so prepared is set in the manner shown in Fig. 10.

A straight continuous strip I is laid along the eave, covered wholly or partly with sheet metal and secured by nailing on the laths or board lining along its upper edge. Over this strip is laid a row II of pieces m, n as shown in Fig. 7 in such a manner that the parts of the course I not covered with sheet 105 metal if such parts are present and the before-mentioned row of nails l are completely covered by the same; the nailing of the elements m, n forming the row II then takes place according to the dotted lines 2. 110 The tongues o formed at the points of the pieces m, n reach under the lower edge of

the layer I, whereby the pieces *m*, *n* have a great resistance against the lifting effect of the wind.

The following rows III, IV and so forth are hereupon arranged so as to completely cover the joints, whereby each higher row covers the rows of nails 3, 4 and so forth of the lower row, and the tongues *o* of each higher row extend under the points of abutment of the lower row.

5 The manner of forming the roof shown in Fig. 11 distinguishes itself from the above manner only by the fact that instead of single pieces *m*, continuous correspondingly 15 serrated courses *z* are utilized.

It will be readily understood that in lieu 20 of the single sheet metal pieces *n* correspondingly cut sheet metal courses may be used, or that for example two or three sheet metal coverings may be manufactured in 25 one piece. In this method of using the sheet metal, there is no waste of material, as the metal courses are so cut that the projecting parts of the one course fall together with the openings in the second course.

Having thus fully described my invention, what I claim is—

1. A roof composed of horizontal layers 30 secured upon the building, said layers comprising sheets, plates having recesses at the rear sides of their inclined lower edges formed by bending backward and upward

said lower edges, the lower angles of said plates being bent squarely backward and upward so as to form recesses wider than 35 those at the sides of said plates, said plates being adapted to overlie said sheets and to engage in their inclined recesses the inclined lower edges of said sheets and to engage in their horizontal recesses the lower edges of 40 the next lower layer.

2. A roof composed of horizontal layers secured upon the building, said layers comprising sheets, quadrangular in their upper portions and tapering in their lower portions, plates having recesses at the rear sides of their inclined lower edges formed by bending backward and upward said lower edges, the lower angles of said plates being bent squarely backward and upward so as to 45 form recesses wider than those at the sides of said plates, said plates being adapted to overlie said sheets and to engage in their inclined recesses the inclined lower edges of 50 said sheets and to engage in their horizontal recesses the lower edges of the next lower layer.

In testimony whereof I affix my signature in the presence of two witnesses.

HEINRICH SCHWARZ.
